UNITED STATES PATENT OFFICE.

CHARLES H. OHLSSON, OF NEW YORK, N. Y., ASSIGNOR TO HEFTER & COMPANY, A FIRM COMPOSED OF DAVID HEFTER AND RAY HEFTER, OF NEW YORK, N. Y.

MACHINE FOR MAKING PAPER-BOX NECKS.

Application filed August 19, 1924. Serial No. 732,911.

To all whom it may concern:

Be it known that I, CHARLES H. OHLSSON, a citizen of the United States of America, residing at New York city, Bronx County, 5 State of New York, have invented certain new and useful Improvements in Machines for Making Paper-Box Necks, of which the following is a specification.

This invention relates to machines for 10 making paper box necks and in particular to a machine which partially covers the neck-piece with a paper binder and then forms and fastens the ends of the same in position ready to be inserted into the box.

15 An object of the invention is to provide a machine which will operate upon a plurality of blanks simultaneously so that the same are completed and discharged from the machine in rapid succession.

20 A further object of the invention is to provide a machine having few parts whereby the same will not clog up and hinder the efficient production of the paper box necks or inserts.

25 A still further object is to provide a machine in which the binder will be continuously fed to the separate neck blanks so that the operation of the machine is continuous at the discharge end of the machine 30 and in which the particular length of binder needed for each individual neck blank will be determined during the passage of the work through the machine.

Referring to the drawings wherein I have 35 shown a preferred embodiment of my invention:

Figure 1 is a top plan view of a machine constructed in accordance with my idea, and shows the method of performing the various 40 operations upon the product as the same progresses through the machine;

Figure 2 is a view in side elevation of the machine taken on line 2—2 of Figure 1 and illustrates the method used in driving the 45 various work performing tools.

Figure 3 is a section in elevation taken on the line 3—3 of Figure 1 and shows the method of feeding the necks through the machine,

50 Figure 4 is an end elevation taken at the discharge end of the machine, some of the parts being omitted for clearness,

Figure 5 is a section taken on line 5—5 of Figure 1 showing one of the discharge head operating cams,

Figure 6 is a side view of one of the neck members prior to its discharge from the machine and after it is ready to be formed on the forming and discharge head,

Figure 7 is a view in perspective of the completed box neck, the outline of a box being also shown in dot and dash lines to illustrate how the neck is positioned therein when placed in cigarette boxes or the like,

Figure 8 is a section taken on the line 8—8 of Figure 1 and shows the knife member in elevation,

Figure 9 is a side elevation of the knife shown in Figure 8 and illustrates the means employed to move the knife vertically to 70 perform a work operation,

Figure 10 is a fragmentary perspective view of the neck blank feeding member and holding frame in which the neck blanks are stored,

Figure 11 is an enlarged view of the forming head and its associated parts,

Figure 12 is an enlarged fragmentary side view of the forming head showing the clamp and its operating parts,

Figure 13 is a bottom plan view of the head and clamp as seen in Figure 12,

Figure 14 is a section taken on the line 14—14 of Figure 1 and shows the binder folder in position to curl the edge of the 85 binder over the neck blank,

Figure 15 is a section taken on the line 15—15 of Figure 1 and shows on an enlarged scale, the advancing member for feeding the blanks to the forming head; and

Figure 16 is a section taken on the line 16—16 of Figure 1 showing the gear connection for operating the forming head.

Referring to the drawings in detail 5 indicates the base plate of the machine which 95 supports the standards 6 in which is journaled the main drive shaft 7 carrying at its outer end the gear 8 which is driven by a pinion 9 and its associated belt pulley 10. The shaft 7 carries intermediate its length 100 a gear 11 from which is driven a train of gears 12, 13, 14, 15, 16, 17, 18 and 19 (see Figure 2) the gears 13, 15 and 17 being affixed to the ends of their respective disk shafts 20, 21 and 22 which are journaled in suitable bearing standards 23 supported on the base 5 and having extended portions 24 for the support of the work bed 25 along which the neck blanks travel. The bearing standards also provide journals for 110

the lower shafts 26, 27 and 28 which carry respectively the gears 18, 14 and 12. The upper and lower shafts carry the feeding disks 29 which are alike and which contact 5 through suitable openings in the work bed 25 to grip and feed the neck blanks 30 along the bed plate 25.

At the feeding end of the machine on the bed plate 25 is attached a blank holder 31 in 10 the bottom of which is disposed a feeder 32 which comprises a notched bar adapted to engage the end of the adjacent neck blank 33, the feeder being reciprocated through the medium of a forwardly extending bar 15 34 which is attached to one end of a slide 35 located on the bed plate 5 the purpose of which will be hereinafter described, the slide being operated by a bar 36 which is engaged by the lever 37 operated through 20 its journal standard 38 by a cam arm 39 which carries a cam roller 40, the latter engaging the cam 41 which is secured to the main drive shaft 7.

A forward movement of the feeder 32 25 will, of course, remove the lowermost neck blank and carry it forwardly until it is caught between the first pair of feeding disks after which it is fed along by the other sets of disks toward the discharge end 30 of the machine. The finished neck has a smooth paper back and edge binder 42, see Figure 6, which is fed into the machine in strip form as shown in Figure 2 where the roll 43 of material is held adjacent a glue 35 pot 44 in which a roller operates to glue one side of the strip 42 as it comes off the roll. After it is gummed or glued, it travels to the intake end of the machine where it passes over suitable pulleys 45 to be introduced into the machine at a point just 40 before the first pair of rollers, or disks and directly beneath the neck blank which is fed into the disks as before described. During the travel of the blank and binder strip 45 through the first pair of rollers the two are glued together and there remains an overlapping edge on the tape. After they pass under the auxiliary pressing roller 46, which is held in a support 47 on the work plate, they pass through a curling or folding device 48 which turns the overlapped edge of 50 the tape around the edge of the neck blank as indicated at 49 in Figures 6 and 7 after which the binder is cut by a suitable travelling knife 50 so that there is a small piece of the binder left extending over the end of the neck blank, this extended portion 51 being ultimately used to fasten the ends of the blank together when the same passes 55 around the forming head to be later referred to.

In that portion of the machine where the knife is located the work bed is cut away as at 52 to allow reciprocation of the knife 50. This knife travels at the same speed

as the feed of the blanks along the bed or work plate and as each blank is led to the machine it is slightly spaced from the preceding blank so that when they reach the knife the space between two blanks always 70 coincides with the knife so that they both travel together while the knife is reciprocated up and down to cut the binder obliquely as shown in Figure 6 to leave it extending out beyond the end of the neck 75 blank to form a binding or connecting flap. The knife is slidably mounted vertically in a reciprocable upright 53 which passes downwardly through the knife support 54, and through suitable slots in both the bottom of the slide and bed plate 5. The upright 53 carries at its lower end the cam roller 55 which engages a grooved cam 56 fastened beneath the base plate 5. Upon a movement of the slide 35 towards the discharge end of the machine the knife will be carried therewith but its cam roller will travel through the lower groove of the cam 56 (see Figures 8 and 9) to cause a downward movement of the knife blade 58 which 90 will of course sever the binder between the ends of adjacent neck blanks. Upon the return movement, the roller will travel through the upper groove of the cam and keep the knife raised. Suitable adjustments 95 of the knife may be made through medium of the set screws 59 and sliding saddles 60.

After the blank or neck has passed the knife it is carried forward by another set of disks mounted on the shaft 22, after 100 which it is engaged by a hook 61 (see Figure 15) which moves one end of said blank into position beneath the forming head 62. The hook 61 is carried on a link 63 which is supported on a stub shaft 64 operated through 105 the medium of a cam arm 65 carrying at its end the usual cam roller 66 which is operated by the cam 67 mounted on the shaft 22.

The forming head 62 revolves and as the blank is scored transversely as at 68 (see 110 Figure 6) at which points it can be bent, it will, upon a revolving movement of the square forming-head 62 be bent into rectangular shape around the head, and the extended tab portion 51 which has been cut in 115 the binding strip adjacent one end of the blank will hold the ends together to form the completed box neck as shown in Figure 7.

The forming head 62 is of course rectangular in shape and comprises an inner work receiver or carrier block 69 which has sliding engagement with the open end of the head 62 and is so arranged that, when a neck-piece which has been formed thereon 120 and completed, a sliding movement of the head 62 over the block 69 will remove the neck and place it over an adjacent stationary receiving block 70 where the joined ends 125 of the neck are firmly pressed together by 130

a block 71 carried on the end of a lever 72 pivoted as at 73 relatively to the work bed plate, and having an extended cam arm 74 which engages a suitable cam 75, the latter 5 of which causes operation of the block to press against the joined ends 76 of the formed neck piece periodically.

The mechanism for operating the head and its associated parts consists of a counter 10 shaft 77 which carries at both ends the gears 78 and 79, the latter of which is toothed approximately three quarters of its circumference, the gear 78 being driven by the intermediate gear 19 which forms part of the 15 gear train which operates the various disks and cams before referred to.

Mounted upon the base plate 5 is a standard 80 carrying in one portion 81 thereof the end of a through shaft 82 which carries at 20 its opposite extreme end the neck receiving block 70. Another portion 83 of the standard 80 carries the flanged end of a tubular shaft 84 which surrounds the shaft 82, and terminates in the neck carrier block 69. Surrounding the shaft 84 is still another tubular shaft 86 which at one end is flanged as at 85 so that it can be held in revolvable relation with an upright 87 which is carried on a slide 90 held in a suitable guide 89 which is 30 affixed to the base 5 of the machine, in any suitable manner.

The shaft 86 carries at its opposite end, the forming head 62 which is hollow, and open at one end to receive the neck carrier block 69, the head 62 being slideable relatively thereto. The shaft 86 carries another tubular shaft 88, the end of which is doubly flanged as at 91 between the flanges there being disposed the ends of a forked lever 92 40 which is pivoted as at 93 to the slide and has an extended arm portion 94 which is engaged by a rock arm 95 (see Figure 1), so that when the latter is operated it causes sliding movement of the shaft 88, which carries at 45 its opposite end the disk 96 which operates a gripper arm 97 forming a part of a gripper mechanism that is embodied in the head 62, and to which reference will be made herein-after.

50 The shaft 88 carries intermediate its ends the sleeved disk 98, the sleeve 99 of which passes through a standard 100 which is mounted upon the slide 90. The free end of the sleeve 99 carries a gear 101 which is operated by the aforementioned gear 79 as will be later described. The gear 79 and disk 98 abut against the opposite sides of the standard 100, and the disk 98 carries near its periphery a pin 102 which passes through the 55 disk 96, head 62 and into block 69, the disk 96 being slideable on said pin. This pin is, of course, used to transmit a turning movement from the gear 101 to the head 62 and block 69, the head being also slideable on the pin. 60 The end of the slide 90 is engaged by a rod 65

103 which is connected through the medium of an extension 104, to a rock arm 105 which is carried on a suitable stub shaft 106 supported in a standard 107 and having disposed at its opposite end a cam arm 108 70 which is operated by a suitable cam 109 carried on the end of a shaft 110 which is operated from the main drive shaft 7 through the medium of bevel gears 111.

This shaft 110 also carries a cam 112 which 75 operates a cam arm 113 carried on an adjacent shaft 114 which is mounted in suitable brackets and carries at its end the rock arm 95 hereinbefore referred to.

In order for the neck blank to be formed 80 about the block 69 it is necessary that the end of the blank when moved into position beneath the block 69 be gripped firmly and held against one side of the block during a turning movement of the head 62 which 85 forms the blank into a rectangle about the block 69. The gripper mechanism comprises, as before mentioned, a gripper arm 97 which is held against one side of the head 62 in a suitable grooved guide 115 and has an upturned portion 116 abutting against the sliding disk 96, a suitable guide pin 117 being used through the disk and arm 97 to guide the latter. A coiled spring 118 surrounds 90 the pin 117 between the head 62 and upturned portion 116 and tends to keep the arm 97 against the disk 96, so that when the disk has a movement relative to the head 62 there will be an opening or closing movement 95 of the gripper, which consists of a gripper foot 119 pivoted as at 120 to the head 62 and adapted to contact with the carrier block 69 to hold the end of a neck blank in position while the block 69 is revolving to form the same. The foot 119 carries a contact arm 100 121 which engages the neck blank and holds it more securely. The foot is connected by a link 122 to the gripper arm 97, so that any movement of the latter will cause an opening 105 or closing movement of the gripper foot 119. 110

In the operation of the machine, it will be noted that the blanks are fed in simultaneously with the binder and after the latter has been secured to the blank by its passage 115 under the disks it is trimmed as before described by the reciprocating knife after which it is given an advance movement by the hook 61 (see Figure 15) so that the blank is fed to the head 62 or more properly to the forming block 69 where it is held by the gripper while the block is revolved. In order to prevent the blank from bulging outwardly during the revolving of the block I may provide on one side of the latter a 120 spring pressed roller 123 (see Figure 2) which is mounted on the end of a pivoted arm 124 and yielding contacts with the side of the block 69.

The arm 124 is somewhat resilient so that 125 it will give way to the head 62 when the lat-

ter operates to remove the completed blank from the block 69. Another roller 124^A is positioned beneath the underside of the block 69 on the end of a pivoted arm 125 held on a standard 126, the arm 125 being fastened to a rod 127 which is held in a block 128, the block in turn being operated pivotally by the cam arm 129 which engages the cam 130 whereby the roller 124^A is moved away from the block 69 when the head 62 has a discharging movement, the cam being shaped to provide a suitable movement at this time.

The head 62 of course is revolved through the medium of the gears 78, 79 and 101, the gear 79 being partly toothed to allow for a longitudinal movement of the head 62 and its associated parts.

In order to have the revolving movement of the head 62 arrested at the right moment I provide a pivoted stop 131 which is operated through a cam lever 132, stub shaft 133 and operating arm 134 the latter of which engages the lower end of the stop 131 and causes its upper projected end 135 to enter a recess 136 in the disk 98 (see Figures 1, 2, 4 and 11).

The gear 79 is untoothed in one portion to allow a relative sliding movement of the gear 101 so that the latter is not revolved during said movement.

In the operation of the head it will be noted that the shaft 82 is fixed and carries the receiving head 70 while the shaft 84 carries the block 69 and revolves therewith, but has no longitudinal movement. The shaft 86 carried in the standard 87 of course has both revolving and sliding movement the latter being imparted by movements of the slide 90 through the medium of the rod 103 and its associated cam operated parts before described. This shaft 86 carries the head 62 so that any movement of said shaft is partaken of by the head. The slide is given one longitudinal movement for every revolution of the head 62, the movement occurring when the head 62 is stopped in its revolving movement, so that the neck blank formed on the block 69 (see Figure 11) is pushed off and onto the receiving head 70 from which it is removed by the next following neck blank and drops down the chute into a suitable container.

The shaft 88 is of course slidably and revolvably mounted and is revolved by reason of its being suitably keyed to the flange 99 of the disk 98 to which is attached the operating gear 101, the sliding movement being imparted by the lever 92 as before described so that the disk 96 is slid back and forth at the proper movement to open and close the gripper mechanism when a neck blank is fed to the forming block 69. The pin 102 is used to assist in the turning of the head 62 and to prevent revolving movement of the disk 96. The timing of the

movements of the various shafts is carried out by the proper cut of the cams a detailed description of which is thought unnecessary.

It will be seen therefore, that I have provided a machine for making up paper box necks which will not only increase production but will eliminate waste and make a neater neck than has heretofore been possible in machines handling each neck blank individually. 75

It is to be understood that my invention, in its broadest aspects, is not limited to the particular constructions shown, nor to any particular constructions or arrangements of parts by which it has been, or may be, carried into effect, since many changes and alterations may be made in structures shown without departing from the principles of the invention and without sacrificing its chief advantages. 85

I claim:

1. A paper-box neck making machine comprising a blank holder, means for feeding the blanks, means for partially covering said blanks with a binder, a traveling knife member for severing the binder to separate the blanks and means for forming said blanks into necks for subsequent insertion into boxes. 90

2. In a paper-box neck making machine, a blank holder, means for successively and simultaneously feeding the blanks through the machine, means for applying a binder to the blanks, and a longitudinally and vertically operated knife member for cutting the binder to form a tab on each of the blanks during the passage of the blanks and binder through the machine. 95

3. A paper-box neck making machine comprising a blank holder, a binding tape, means for holding the same, means for advancing the blanks and the tape through the machine, and a vertically and longitudinally operated knife for severing the tape whereby a tab will be left thereon by which the ends of the blank may be held together. 105

4. A paper-box neck making machine comprising a holder for separate neck blanks, a binding tape roll holder, means for feeding the separate blanks and the binding tape through the machine, the blanks being superposed on the tape, means for folding one edge of the tape over one edge of said blanks, and a knife adapted to travel with the tape for cutting the tape between the blanks whereby the latter will be separated. 115

5. A paper-box neck making machine comprising a holder for neck blanks, a binding tape holder, means for feeding the neck blanks and tape into the machine in superposed relation, means for attaching the tape to the blanks, a longitudinally movable knife member for severing the tape whereby the blanks will be separated, and a common operating member for actuating said severing knife and said blank feeding means. 125

6. In a paper-box neck making machine, a work bed along which the material to be operated upon is advanced, means for advancing said material, a forming head at the discharge end of the machine, and a gripper on the forming head for gripping said material, upon a movement of said forming head.
7. In a paper-box neck making machine, a blank holder, means for feeding the blanks through the machine, a forming head at one end of the machine to which the blanks are fed, a gripper on said head, means for operating the gripper, when a blank is in position on the head, to grip said blank, and means for releasing said gripper at a predetermined time.
8. In a paper-box neck making machine, a blank holder, a roll of binding material, means for feeding the blanks and binding material to the machine together, means for attaching said binder to said blanks, and a longitudinally movable knife for cutting a tab on said binder adjacent the end of each blank, said tab being adapted to serve as a retainer for holding the blank in shape after it has been formed into a neck.
9. In a paper-box neck making machine a plurality of neck blank feeding members, a forming member around which a neck blank is wound, and a movable sleeve operable over the forming member for discharging the blank after the same has been formed.
10. In a paper-box neck making machine a neck blank receiving member, a gripper for holding the blank on said member during a forming operation, a discharging member operable over said forming member, and means for operating said gripper whereby the same will release the blank upon a predetermined movement of said discharging member.
11. In a paper-box neck making machine, a neck blank forming member, a discharging member and a receiving member onto which the blank is moved after it has been removed from the forming member by the discharging member.
12. In a paper-box neck making machine, a forming head, a blank receiving block in said head, means for revolving said head, and means for moving said head over said blank receiving block.
13. In a paper-box neck making machine, a neck blank forming head, means for imparting to said head a revolving movement, and means for imparting to said head, a longitudinal movement between each complete revolution of said head.
14. In a paper-box neck making machine, a neck blank forming head, means for revolving said head, means for imparting a discharging movement to said head, a roller engaging said head for retaining a blank in place thereon, and means for moving said roller away from the head during a discharging movement thereof.
15. In a paper-box neck making machine, a neck blank forming head, means for imparting to said head a revolving movement, a shaft upon which said head is mounted, a sleeve on said shaft, a slotted disk on said sleeve and a member adapted to engage said slot to stop the revolving movement of said head at a predetermined point.
16. In a paper-box neck making machine, a blank forming head, a block upon which the blank is held, a finish blank receiving member, a stationary shaft in said receiving member, a revolvable shaft in said block carried by the stationary shaft, a shaft in the forming head carried by the revolvable shaft and means for moving said head carrying shaft longitudinally of said other shafts.
17. In a paper-box neck making machine, a blank bending or forming head, a shaft upon which the head is carried, means for revolving said shaft, a tubular shaft surrounding said head carrying shaft, a disk on said tubular shaft, a gripper on the head adapted to be operated by said disk, a slide, a lever pivoted on said slide and adapted to engage the tubular shaft to cause longitudinal movement of the disk, a support for the head-carrying shaft mounted on the slide, and means for imparting longitudinal movement to the slide whereby a relative longitudinal movement will result between the disk and the head.
18. In a paper-box neck making machine, a neck blank holder, a neck forming head, means for advancing the blanks to the head a slide beneath said head, a block within said head upon which the blanks are held, a shaft for said head, a shaft for said block, means for revolving both of said shafts simultaneously a slide, means for reciprocating the same, and a connection between the head carrying shaft and the slide whereby when the slide is reciprocated, the head will be caused to have longitudinal movement relatively to the block.
19. In a paper-box neck making machine, a neck forming head, a block within said head adapted to receive the neck blank, a slide on said head a gripping foot pivotally connected to said slide and said head and adapted to engage the block, and means for operating said slide at a predetermined time to cause operation of said gripping foot.
20. In a paper-box neck making machine, a blank holder, a tape holder means for feeding the blanks successively to the machine together with the tape, a knife for severing the tape between the blanks, means for reciprocating the knife longitudinally of the work and at the same speed as the feed of the work, and means for reciprocating the knife vertically.
21. In a paper-box neck making machine,

a neck blank holder, a tape holder, means for feeding the blanks and tape through the machine, means for turning the tape over one edge of the blanks to form a binder, means for severing the tape to separate the blanks, said means being adapted to cut a tab on the tape adjacent one end of each blank, a forming head around which the blank is bent to

shape, means for revolving said head means for imparting thereto a longitudinal blank discharging movement, and means in contact with said head for acting on the blank tab to cause the same to hold the ends of the formed blank in proper shape. 10

CHARLES H. OHLSSON.
